UNITED STATES PATENT OFFICE.

LESTER KIRSCHBRAUN, OF CHICAGO, ILLINOIS.

PROCESS AND APPARATUS FOR MAKING PAPER.

Application filed March 28, 1924. Serial No. 702,482.

This invention relates to improvements in process of making paper, and refers more particularly to a process for making multiply sheets, in which, between certain plies 5 there is interposed a liquid repellent medium.

By means of the present invention, the liquid repellent medium is preferably interposed between given plies as the paper is 10 being formed, and also by means of the present invention two or more separate sheets may be produced after the paper has been dried, each of which sheets carries liquid repellent material on its surface.

15 The objects and advantages of the invention will more clearly appear from the following description, in which—

Fig. 1 is a somewhat diagrammatic view, partly in side elevation and partly in vertical section, of the cylinder molds of a multi-cylinder paper machine, on which the process may be carried out.

Fig. 2 is a somewhat diagrammatic view of the dry end of the machine, showing the 25 balance of the hot driers and winding up reels.

Fig. 3 is a view, on an enlarged scale, of the application roll and box, forming a feature of the invention.

30 Referring to the drawings, 1 designates the vats in which are mounted the cylinder molds 2. Above the cylinder molds are the usual couch rolls 3, blanket 4 and drum roll 5. Mounted above the blanket 4 are the adjustable depression rolls 6, of which there are two in the present instance. It will be noted that, in this apparatus, the vats are spaced apart to accommodate the application boxes. The object of having two application 40 boxes is to be able to use one in the event the other is out of order, or needs cleaning, and thus avoid the necessity of stopping the operation, or to provide for a plurality of applications.

45 The construction of the application boxes and rolls is shown more clearly in Fig. 3, in which 7 designates the application box and 8 the roll. The roll 8 may be covered with two or three inside layers of say, 14 50 mesh wire and one outside layer of 50 mesh wire, and the roll may be driven. The box 7 may be provided with an overflow dam 9 and outlet pipe 10, provided with a suitable valve 11. To the pipe 10 is suitably connected a swinging pipe 12 which can be raised or lowered in the funnel 13, which

funnel 13 is connected by pipe 14 to the storage tank 15. The arrangement is such that the emulsion may be maintained at any level in the box 7. From the storage tank 15 60 the previously prepared emulsion is fed by pump 16 through line 17 to the head box 18. This head box 18 in turn connects through pipe 19 having control valve 20 to the application box 7. By means of this arrangement the emulsion may be continuously applied to the underface of the sheet as it leaves the right hand set of cylinder molds. As the coated sheet passes to the left hand 65 set of cylinder molds, it is obvious that a 70 liquid repellent layer such as asphalt and the like will be interposed between the upper and lower plies of the sheet.

The sheet, after passing over the various pressure rolls and driers, finally passes out 75 over the last of the hot driers designated 21 and is then manually separated and one sheet guided over the talc roll 22 rotating in the talc box 23 while the other sheet is drawn over the roll 24, supplied with talc 80 from the talc box 25. Separating rolls 26 and 27 are preferably provided with high pressure steam, say, at about 150 pounds pressure. The calendar rolls, as shown more clearly in Fig. 2 may be by-passed and the 85 sheets carried directly to the winding up reels 29, 30, 31 and 32. These reels are in pairs so that the reel *a*, for example, is winding up the new sheet while the reel *b* is unwinding the previously wound sheet, re-winding it on another spool. The manner in which this is accomplished, is obvious and need not be described in more detail.

90 In carrying out the process, I first make an emulsion, preferably of a non-adhesive 95 character, of asphalt or other bituminous material, with clay or other argillaceous emulsifying agent and water. The manner in which this emulsion is made is fully described in my issued patents and this specification need not be encumbered with a detailed description thereof. This previously prepared emulsion may be fed from the storage tank 15, in the manner heretofore described, into the application box 7. The 100 screen covered application roll picks up the emulsion and applies it to the underface of the oncoming sheet. The layer of emulsion is, of course, squeezed between the upper and lower plies from the left and right hand 105 cylinder molds respectively and then as the sheet passes over the driers, the water is re-

moved and a sheet with an asphalt or similar bituminous layer between the outer plies is formed. As the sheet passes over the last driers, it is manually separated and the two or more separated sheets pass over the talc rolls 22 and 24. By this method two independent sheets are formed, each of which has on one of its surfaces a coating of a liquid repellent or waterproof material such as asphalt or bitumen. It is to be understood that either one or both of the application rolls may be used at one time, and further, that as many cylinder molds and application boxes may be used as is desired. Furthermore, the asphalt or other bituminous layer might, if desired, be interposed between say, the two upper plies and the four lower plies. This obviously could be accomplished by shifting the position of the application boxes relative to the cylinder molds, as for example, placing the cylinder boxes between the second and third of the right hand cylinder molds, or if desired, between the first and second of the left hand cylinder molds. The particular apparatus forms the subject of a separate application.

It is to be understood that the separating operation may be carried on as described, or may be conducted as a subsequent operation on a separate piece of equipment not directly or continuously co-ordinated with the paper making machine per se. In such instances the paper making operation would be conducted in accordance with the disclosure of co-pending application, Serial No. 702,314 filed March 27th, 1924, and the paper wound up in large rolls, after which it is subjected to the separating or splitting operation.

I have shown and described a process of forming two sheets of paper having waterproofing medium on one surface of each. It will be clear that by applying between successive plies, layers of waterproofing material in the manner described, more than two waterproof sheets can be simultaneously produced during the same paper-making operation.

The advantages of an operation of this kind, whereby a plurality of sheets of light paper are formed and waterproofed simultaneously, is obvious. It is well known that in order to have maximum production upon an ordinary board machine such as described the limiting factors of speed militate against the production of maximum tonnage of light weight paper or board. It will be readily seen that where the average board machine operates to produce a satisfactory tonnage in the production of paper from 18 to 35 caliper, the production of an 8 point sheet on such a machine becomes a slow and expensive operation, but by employing the process of the present invention, it is perfectly feasible to simultaneously produce two sheets of say, 8 points and 12 points each in caliper

at substantially the same production rate at which the machine operates for a 20 point sheet, or it is possible to produce say, two 8 point sheets at practically the same production rate at which a single 8 point sheet is produced.

Further, the process herein described obviates the necessity of running the waterproof ply in direct contact with the blankets and presses of the paper-making machine where it is desired to make paper having a waterproofing material on the surfaces.

I claim as my invention:

1. A method of making waterproofed paper, comprising forming on a paper machine, a plurality of fibrous plies, interposing during the paper forming operation a layer or layers of liquid repellent material between predetermined inner plies by causing the wet plies to pass in contact with a rotating surface carrying said liquid repellent material, uniting the plies to form a sheet, separating the sheet at the point of the interposed liquid repellent layer and drawing off such separated sheets. 90

2. A method of making waterproofed paper, comprising forming on a paper machine, webs on certain cylinder molds, forming other webs on other cylinder molds, interposing layers of emulsified waterproofing material between the opposed wet surfaces of certain webs by bringing certain webs into contact with a rotating element carrying said liquid repellent material, in then uniting the webs and layers into a single sheet and passing it over the usual driers, in then separating the sheet at said interposed waterproofing layers, and independently removing said separated waterproofed sheets. 100

3. A process of simultaneously producing a plurality of sheets having waterproofing material on the surface thereof, comprising forming a plurality of fibrous plies on a paper machine, causing given intermediate plies to be brought into contact with the surface of a rotating element carrying waterproofing material whereby a layer of waterproofing material is applied to said fibrous surface, forcing the plies together on either side of said layer, passing the same over driers and then separating the same into independent sheets at the point where said waterproof layer is interposed. 110

4. In an apparatus for making paper, the combination with cylinder molds for forming a multiply sheet, means for applying liquid repellent layer between intermediate plies and means for separating the sheet along the line of said layer, and means for independently removing the separated sheets. 120

5. In an apparatus for making paper, the combination with cylinder molds for forming a multiply sheet, means for applying liquid repellent layers between intermediate plies and means for separating the sheet 130

along the line of said layers and means for independently removing the separated sheets.

6. A process of simultaneously producing a plurality of sheets each having waterproofing material on a surface thereof, comprising forming a plurality of fibrous plies on a paper machine, causing given intermediate plies while still wet to have applied thereto a pre-formed film of waterproofing material, forcing the plies together on either side of said film to produce a multi-ply sheet, passing the said multi-ply sheet over driers, separating said multi-ply sheet into independent sheets at the point where said waterproofing layer is interposed.

7. A process of simultaneously producing

a plurality of sheets each having waterproofing material on a surface thereof, comprising forming a plurality of fibrous plies on a paper machine, causing given intermediate 20 plies while still wet to have applied thereto a pre-formed film of waterproofing material, forcing the plies together on either side of said film to produce a multi-ply sheet, passing the said multi-ply sheets over driers, 25 separating said multi-ply sheets into independent sheets at the point where said waterproofing layer is interposed, while at a temperature sufficiently elevated to permit separation.

LESTER KIRSCHBRAUN.
